UNITED STATES PATENT OFFICE.

OTTO SCHÜTTE, OF CZERSK, GERMANY.

BLANK CARTRIDGE.

SPECIFICATION forming part of Letters Patent No. 726,579, dated April 28, 1903.

Application filed September 22, 1902, Serial No. 124,451. (No model.)

To all whom it may concern:

Be it known that I, OTTO SCHÜTTE, a subject of the King of Prussia, Emperor of Germany, residing at Czersk, Prussia, German Empire, (post-office address am Bahnhofestrasse, Czersk, East Prussia,) have invented certain new and useful Improvements in Blank Cartridges, of which the following is a full, clear, and exact description.

10 The blank cartridge forming the subject-matter of my present invention is designed to possess the same detonating force and the same back stroke as a real cartridge without, however, possessing the disadvantages of the 15 blank cartridges hitherto used, which, owing to the hollow wooden shot-casing employed in the same not being destroyed, is often expelled with such force as to occasion very serious wounds. For this reason the blank 20 cartridges hitherto used require a zone of danger of one hundred meters.

25 In the accompanying drawings one form of construction of my improved blank cartridge is shown in several views.

Figure 1 is a longitudinal section of a full-sized specimen. Fig. 2 represents the forward part of Fig. 1 on an enlarged scale, and Fig. 3 is a section on the line *m n* of Fig. 2.

30 My improved cartridge consists of the shell *d*, the priming *e*, the charge *c*, a felt wad *b*, and closing or end plate or wad *a*. The shell *d*, which is made, preferably, of one piece, possesses the form and length of a real cartridge, including the projectile, and contains a 35 comparatively strong charge *c*. Its forward part, which represents the projectile, is hollow and of considerably-smaller diameter than the rear, which represents the shell. The felt wad *b* is inserted into the cartridge, pressed 40 tightly against the charge *c* in the shell, and held against movement by the inwardly-deflected portions *f*, formed by the reduction in the shell. A conical end plate or wad *a*, of 45 cork or elder-pith, rendered non-hygroscopic and waterproof by some suitable agent, is fitted into the forward end of the cartridge,

which is turned inwardly and provided with inwardly-turned lugs *h*, against which the plate *a* bears. On firing the charge *c* can only 50 expel the felt wad *b* through the long front part of the shell *d* relatively slowly, so that complete combustion of the charge occurs, and the detonation is accordingly greater. Both the felt wad *b* and the plate or wad *a* are pressed out of the casing, and this requiring force, owing to the impediments in their path, the back stroke of the rifle is obtained 55 as with real cartridges. The gases after leaving the shell *d* destroy the felt wad *b* and the plate or wad *a* in the barrel of the rifle after 60 this has been accomplished in being expelled from the shell *d*. The zone of danger can be reduced to ten meters with these blank cartridges.

Having thus described my invention, what 65 I claim is—

1. A blank cartridge comprising a metallic shell of a length equal to the shell of an ordinary cartridge and its projectile, reduced at its forward portion to correspond to the external appearance of the projectile, a charge 70 of powder in the rear of the shell, and a wad holding the powder and being held against movement by the shoulder formed by the reduction of the shell.

2. A blank cartridge comprising a metallic shell of a length equal to the shell of an ordinary cartridge and its projectile, reduced at its forward portion to correspond to the external appearance of the projectile, said forward end being open, a charge of powder in the rear of the shell, a wad holding the powder and being held against movement by the shoulder formed by the reduction of the shell, and a wad of easily-destructible material closing 75 the open end of the shell.

In witness whereof I have subscribed my signature in presence of two witnesses.

OTTO SCHÜTTE.
